UNITED STATES PATENT OFFICE.

FRANK B. CHASE AND EDGAR P. REDFIELD, OF NEW YORK, N. Y.

DESIGN FOR A DUPLICATE-WHIST BOARD.

SPECIFICATION forming part of Design No. 28,959, dated June 28, 1898.

Application filed January 11, 1898. Serial No. 666,369. Term of patent 14 years.

To all whom it may concern:

Be it known that we, FRANK B. CHASE and EDGAR P. REDFIELD, citizens of the United States, residing in the city, county, and State 5 of New York, have invented and produced a new and useful Design for Duplicate-Whist Boards, of which the following is a specification, reference being had to the accompanying drawings, forming part thereof.

- In the accompanying drawings, Figure 1 is a plan view of a duplicate whist board embodying our new design. Figure 2 is a sectional view taken on the line $x-x$ of Figure 1. The leading or material feature of our design, as shown in the drawings, consists of a board A formed in the similitude of an eight-pointed star, and as to one face provided with a central boss B.
- The points or rays of the star are, as shown, alternately larger and smaller, the larger being designated a and the smaller a' .

At the points of intersection of the opposing edges of the adjacent points or rays are formed notches b , while grooves c in the face 25 of the board opposite that on which the boss B exists, subtend the points a' of the star, and terminate or open at both ends in the notches.

Having thus described our invention, what 30 we claim as new, and desire to secure by Letters Patent, is—

The design for a duplicate whist board, as herein shown and described.

In testimony that we claim the foregoing as 35 our invention, we have hereunto signed our names this 22d day of December, A. D. 1897.

FRANK B. CHASE.
EDGAR P. REDFIELD.

In presence of—
OWEN WARD,
W. BENJAMIN.
